United States Patent Office

Des. 179,147
Patented Nov. 6, 1956

179,147

REFRIGERATOR CABINET

Robert E. Munz, Jeffersontown, and William F. Saenger,
Louisville, Ky., assignors to General Electric Company,
a corporation of New York

Application November 29, 1955, Serial No. 39,085

Term of patent 14 years

(Cl. D67—3)

FIG. 1

FIG. 2

Figure 1 is a perspective view of a refrigerator cabinet embodying our new design; and

Figure 2 is a second perspective view of said refrigerator cabinet showing the interior thereof.

The side of the refrigerator cabinet which is not shown in Figures 1 and 2 of the drawings is substantially like the side shown.

We claim:

The ornamental design for a refrigerator cabinet, substantially as shown and described.
